UNITED STATES PATENT OFFICE.

GILBERT WRIGHT, OF SCHENECTADY, NEW YORK, ASSIGNOR TO GENERAL ELECTRIC COMPANY, A CORPORATION OF NEW YORK.

ELECTRIC SWITCH.

1,289,996.

Specification of Letters Patent. Patented Dec. 31, 1918.

Application filed May 5, 1915. Serial No. 25,909.

To all whom it may concern:

Be it known that I, GILBERT WRIGHT, a citizen of the United States, residing at Schenectady, county of Schenectady, State of New York, have invented certain new and useful Improvements in Electric Switches, of which the following is a specification.

My invention relates to electric switches and the like, and more particularly to the construction and inclosure of electric switches in such a way as to minimize the danger of operating and working with them and with the apparatus that they control. My invention comprises various features and details of operation and construction and various combinations and arrangements of parts that can best be disclosed by the description of a particular apparatus embodying them, —its scope being indicated in my claims.

20 In the accompanying drawings, Figure 1 is a side elevation of the apparatus with the switch closed, the side of the inclosing casing being cut away.

Fig. 2 is a view from beneath, various parts being in section at a surface corresponding to the broken line 2—2 in Fig. 1.

Fig. 3 is a view similar to Fig. 1 with the switch open.

Fig. 4 is a side view of a locking device.

30 Referring first to Figs. 1 and 2, it will be seen that the apparatus shown comprises a switch proper 10 of ordinary three blade construction mounted on a base 11 of slate or other insulating material. Also mounted 35 on the base 11 and appropriately connected with the switch 10 are fuse holding means 12 shown as in the form of receptacles of the Edison screw type adapted to receive ordinary plug fuses. The switch base 11 is 40 secured to the bottom of a casing 13 which incloses the switch 10 and the receptacles 12 and other accessory parts. This casing 13 is shown as a substantial sheet-iron box with its upper and lower ends rounded in front; 45 preferably its joints or seams are electrically welded. The box proper has upper and lower openings where thus rounded, and rounded covers 14 and 15 are provided to close these openings. The cover 14 (for as 50 the covers 14 and 15 are exactly alike only one of them need be described) has a two-eared bracket 16 of channel-like form welded to its lower edge, and this bracket 16 fits between brackets or ears 17, 17 fastened to

the front portion 18 of the box proper between the aforesaid openings and is pivoted to said brackets 17 by a pin or bolt 19. Through switch actuating means presently to be described the covers 14 and 15 are so interlocked with the switch 10 that the latter 60 must be actuated to open the circuit before either cover can be opened. The covers 14 and 15 always tend to close under the action of tension springs 20, 20. The upper cover 14 gives access to the switch 10; the lower 65 cover 15 to the fuse plug receptacles 12.

The switch apparatus shown being intended for push and pull operation and also to give a quick make and break, its actuating means includes a reciprocating operating 70 member 21 that extends through the casing front 18 and a spring mechanism interposed between said member and the switch proper 10. The member 21 comprises two parallel strips 23, 23 of sheet metal secured together 75 and spaced apart in any suitable way, and is provided with a convenient handle. The member 21 slides between the brackets 17, 17 and between the ears of the brackets 16, 16 and in ways in a channel-like girder 24 that 80 extends across the casing 13 behind the front portion 18. These ways, it will be seen, are formed by the sides of the channel 24 and by depending extension pieces 25 attached to brackets or ears 26 secured to the lower 85 side of the front portion 18 by screws 27 that extend down through the brackets 17, 17.

Coming, now, to the spring mechanism through which the switch 10 is ordinarily actuated, it will be seen that on the inner 90 side of each of the bracket extensions 25 a rocker member 28 is pivoted at 29, and to the ends of the rockers 28, 28 (on their outer sides) the forward ends of links 30, 30 are pivoted by means of a pin 31. The rear 95 ends of the links 30, 30 are pivoted at 32, 32 to lugs or ears attached to the inner side of the insulating bar 34 that unites the free ends of the switch blades. On the pin 31 (but between the ends of the rockers 28, 28) 100 is pivoted a block 36 in which is secured one end of a rod 37 which slides freely through a block 38 pivoted at 39 between the lower ends of the strips 23, 23 of which the member 21 is composed. On the rod 37 105 between the blocks 36 and 38 is a helical compression spring 40, and secured to the free end of the rod 37 is a short compression

spring 41 that serves mainly to cushion the movements of the parts and to take up backlash.

From the foregoing description it will be evident that when the parts are in the positions shown in Fig. 1 and pressure is applied to the member 21 to push it inward the pivot 39 will move downward and toward the pivots 29, 29, and that the spring 10 will be compressed and will exert on the block 36 a pressure tending to hold the switch 10 closed. As, however, the pivot 39 passes the line of centers of the pivots 29, 29 and 31,—which is a dead center for the parts 28, 28 and 37,—the spring 40 will be left free to expand and throw open the switch 10 as shown in Fig. 3; and at the same time it will throw the member 21 inward as also shown in that figure. This action will be very rapid and powerful, so that any arc that may be drawn will be quickly broken. When the parts are in the positions shown in Fig. 3 and a pull is exerted on the member 21 the switch 10 will be closed with a similar quick action, and member 21 pressed to its outward limit.

In the lower end of the member 21 is fixed a pin 42 whose protruding ends slide in slots in the bracket extensions 25, 25 and thus limit the in and out movement of the member. It will be seen that if the spring 40 should fail to throw the switch 10 in either direction,—whether from sticking of the parts, breakage of the spring, or any other cause,—the pin 42 will come against one end of an enlarged foot portion 43 of each of the rockers 28, 28 and either positively open or close the switch or start it so as to cause the spring to throw it.

40 So far nothing has been said regarding the interlocking of the switch 10 with the covers 14, 15 except that it is accomplished through the switch operating means. It has, however, been pointed out that the 45 strips 23, 23 of the operating member 21 slide just between the edges of the ears on the brackets 16, 16. From this fact and the various figures of the drawing, it will be evident that when the member 21 is pulled 50 out and the switch 10 closed as in Fig. 1 the edges of said strips 23, 23 will effectually block such movement of said ears as must take place when the covers 14, 15 are swung open; whereas when the member 21 is pushed 55 in to open the switch 10 as shown in Fig. 3 the notches 44 in the strips 23, 23 will be opposite said ears and allow the covers to swing quite freely. A very slight outward movement of the member 21 from the position of Fig. 3, wholly insufficient to throw the switch, will block the covers 14, 15 completely. Finally, it will be observed that when the parts are as shown in Fig. 3 and the cover 14 has been opened it is possible 60 to take hold of the member 34 with the hand

and move the switch 10 toward the closed position, but that before the pivot 39 has passed the dead center or the switch blades have approached their contacts sufficiently to cause any danger of arcing the lower 70 ends of the rocker portions 43 will encounter the pins 42 and movement will be blocked. It follows, therefore, that the switch 10 cannot be closed except by the operating member 21; neither can it be 75 brought to an intermediate position where it will remain if released.

It will be observed that in the member 21 there is a slot 45 and that the brackets 16, 16 have extensions 46, 46 that approach one 80 another very closely and overhang this slot when the switch 10 is open and the covers 14, 15 are closed (see Fig. 3). By inserting the locking element 50 in this slot 45 and snapping a padlock 51 in one of the holes 85 52, 53 therein it will be rendered impossible to manipulate the members 21 to close the switch 10 or to open either of the covers 14, 15. By inserting the element 50 in similar slots 47, 47 in the bracket ears 17, 17, 90 opening of the cover 14 will be prevented without interference with the cover 15 or with the manipulation of the switch 10. The various holes 52, 53 in the element 50 allow the switch apparatus to be controlled 95 by several persons, as the electrician in charge of repairing the motor controlled by it and the machinist in charge of machinery driven by said motor,—so that each will be protected against any other by merely using 100 his own padlock.

What I claim as new and desire to secure by Letters Patent of the United States, is:—

1. The combination of a casing having an 105 opening and swinging closure means therefor, an electric switch in said casing, operating means for said switch including a member which interposes directly in the path of swing of said closure means except 110 when the switch is in open position, a yieldable connection between said operating means and said switch whereby the latter is moved with a snap action, and means for locking the switch open while the closure 115 means remain open.

2. The combination of a casing having an opening and swinging closure means therefor, a switch in said casing, reciprocating actuator for said switch including a member which interposes directly in the path of swing of said closure means except when the switch is open, a rocker connected to said switch and mounted on a stationary axis, and a spring connection between said rocker 120 and said actuator adapted to be moved from side to side of said rocker axis by said actuator.

3. The combination of a casing having an opening with a door therefor, a switch in 125

- said casing, a reciprocating actuator for said switch having a member which directly interposes in the path of swing of said door except when the switch is in open position, 5 a rocker connected to said switch, a spring connecting said rocker to said actuator, and interlocking means to prevent the closure of said switch while said door remains in open position.
- 10 4. The combination of a casing having openings at opposite ends of one side and an intervening central portion, doors hinged to said central portion, a switch in said casing, and a reciprocating actuator for said switch having a notched member passing through said central portion adjacent said hinges and adapted to interpose directly in the path of swing of said doors except when said switch is open.
- 15 5. The combination of a casing having an opening and movable closure means therefor; a switch in said casing; and actuating means for said switch including a pull and push operating member which extends out through the wall of the casing in the path of movement of said closure means in opening, said member being notched so as to permit opening of said closure means when the switch is open, a spring mechanism interposed between said operating member and the switch and adapted to give a quick make and break, and additional means associated with said member for opening and closing the switch positively if said spring mechanism fails to do so.
- 20 30 35

In witness whereof, I have hereunto set my hand this 30th day of April, 1915.

GILBERT WRIGHT.
